Application November 7, 1945, Serial No. 627,244

10 Claims. (Cl. 201—63)

1

The present invention relates to non-linear resistance elements, for use in rheostats and potentiometers and in other devices, and made preferably by winding resistance wire on an insulating strip or support. The object of the invention is the production of a new and improved resistance element of this character.

The invention may be considered as being an improvement on or further development of the invention disclosed in my Patent No. 2,468,144, granted April 26, 1949.

In the pending application referred to, a non-linear resistance element is disclosed comprising a resistance wire of uniform diameter wound on a strip of uniform width and thickness, and having a non-linear resistance curve which is obtained by a varying or changing spacing of the turns of the winding. The spacing is referred to as a quantity Q , defined as the ratio of the space between turns to the diameter of the wire, and it is pointed out that permissible values of Q range from a minimum of about .25 to a maximum of about 4. This limited range of Q limits the utility of the invention to cases where the desired resistance curves do not depart very much from straight lines.

The present invention, on the other hand, is free from the above limitation and may be used in the manufacture of a resistance element having any resistance curve that may be required, so far as known. At any rate, the useful field that may be covered through the medium of a varying turn spacing is very greatly extended. This result is accomplished, in a typical case, by employing a continuous resistance wire comprising two sections of different diameters joined by a tapered section and by winding the wire on the strip with a spacing which varies in each section in the proper manner to give the resistance element the required resistance curve.

The invention will be described more in detail hereinafter, reference being had to the accompanying drawings, in which—

Fig. 1 is a plan view of a resistance element embodying the invention;

Fig. 2 is a graph showing the resistance curve of the resistance element of Fig. 1; and

Fig. 3 is a diagrammatic representation of the wire with which the resistance element is wound.

Referring now to Fig. 1, the strip 10 is made of Bakelite or other suitable insulating material and is of uniform width and thickness. Terminals 11 and 12 may be made of thin sheet copper and are located near opposite ends of the strip, respectively, where they are secured in place by

rivets as shown. The strip also has perforated end extensions 13 and 14 by means of which it is held in the winding machine during the winding operation.

5 In the specific resistance element which is shown and described herein, the dimensions of the strip as to width and thickness are such that the length of each turn is .915 inch. The distance between terminals, or the length of the winding space, is 3 $\frac{3}{8}$ inches.

The winding is made of a suitable resistance wire which may have a resistance of 600 ohms per circular mil foot, for example. The other values given herein are based on the foregoing 15 value for the specific resistance of the wire.

A resistance wire ready for winding is shown in Fig. 3 and comprises a section 17 of wire which is 5.6 mils in diameter and 114.1 inches long, a tapered section 18 which is 33 inches long, and a section 19 which is 3.377 mils in diameter and 20 113.7 inches long. These sections preferably form a continuous wire 310.8 inches in length which is wound on the strip 10 between the terminals 11 and 12. The wire actually is longer than this since surplus wire must be allowed at each end for wrapping around terminals 11 and 12 and an additional amount at the end of section 19 for operation of the winding machine.

The wire may be made by means of a wire tapering apparatus such as is disclosed in the pending application of Thomas B. Gibbs et al., Serial No. 525,764, filed March 9, 1944. According to the disclosure in this application, an electrolytic cell system is provided comprising a large 35 number of serially related electrolytic cells in which the wire or wires to be tapered function as the anode and are reduced in diameter by anodic reduction. In using this apparatus to make wires such as shown in Fig. 3, a plurality 40 of wires having a diameter of 5.6 mils are placed in the electrolytic cell system and are pulled through at the proper speed to reduce them to a diameter of 3.377 mils. This operation is continued until somewhat more than 113.7 inches 45 of each wire has been pulled entirely through the electrolytic cell system, thereby forming a cylindrical section such as 19 at the end of each wire. The current is then shut off, but the pulling operation is continued until the sections which were in the bath at the time the current was shut off (tapered from 5.6 mils to 3.377 mils) and enough more to make the cylindrical sections such as 17 have been pulled through. The wires are pulled through the electrolytic cell system by winding them on spools and are cut off 50

next to the electrolytic cell system when the operation is completed. The tapered sections are equal in length to the length of the electrolytic cell system, which in the case of the apparatus available for making the wires described happened to be 83 inches. Shorter tapered sections may be made by cutting out one or more cells, and longer tapered sections can be made by the method described in the Gibbs et al. application referred to.

The wire is wound on the strip 10 by means of a winding machine such as described in the pending application of Gilman et al., Serial No. 563,522, filed Nov. 15, 1944, now Patent No. 2,466,227, issued April 5, 1949. The winding is started at the left hand end of the strip and includes a few turns which are wrapped around the projecting end of terminal 11. These turns are put on by operating the machine by hand and are so adjusted as regards number and spacing that the beginning of section 17 of the wire, which is preferably marked when the wire is made, is in the first turn beyond the strip. The machine winds on the rest of the wire automatically and is so set up that the end of section 19 is reached in the last turn which does not overlap terminal 12. After about half a dozen or so turns have been wrapped around terminal 12 the machine stops automatically.

When the winding is completed the ends are secured to the strip by small pieces of tape or in any other suitable manner and the wound strip is removed from the machine. The wire is then preferably soldered to terminals 11 and 12 and the surplus is cut off.

The completed resistance element may be utilized in the manufacture of a potentiometer of known mechanical construction, including a cylindrical casing made of insulating material. For this purpose the strip 10 is cut off at both ends along the dotted lines 15 and 16 and is bent into a circular formation so that it can be inserted in the casing, where it is held in place in any suitable manner. The potentiometer may also include a shaft rotatably mounted on the casing and carrying a wiper which is adapted to successively engage the turns of the resistance element as the shaft is rotated. The shaft may also have a calibrated dial and suitable stops may be arranged so that when the dial is in zero position the wiper will engage the last turn which is soldered to terminal 11 whereas when the dial is fully rotated the wiper will engage the first turn which is soldered to terminal 12.

It will be understood that the resistance element described is so designed that the resistance curve of the potentiometer in which it is used will conform to a particular required resistance curve. This curve is shown in Fig. 2 and is constructed by plotting resistance in ohms against percentage of wiper rotation ranging from 0 rotation to 100 percent rotation. The curve is defined by the equation

$$Y = \log^{-1} \left(\frac{X}{100} + 2 \right) - 100$$

in which Y is equal to the resistance in ohms and X is equal to the percentage of rotation of the potentiometer wiper. The resistance is measured between terminal 11 and the wiper terminal.

The curve, Fig. 2, may be considered as being composed of three sections, R1, R2 and R3. Section R1, as measured along the X axis, extends from 0 percent rotation to 45 percent rotation, section R2 extends from 45 percent rotation to 70

percent rotation, while section R3 covers the range from 70 percent rotation to 100 percent rotation. Fig. 1 is so aligned with Fig. 2 that distance along the winding can readily be translated into percentage of rotation, or vice versa, whereby it can be seen that sections R1, R2 and R3 of the curve correspond, respectively, to the sections 17, 18 and 19 of the winding.

The resistance for any percent of rotation or 10 for any distance along the strip can be read by projecting the corresponding point on the curve to the Y axis. Thus when the potentiometer dial is set at zero, the wiper being then in engagement with the last turn which is soldered to terminal 11, the resistance is zero. As the dial and wiper are rotated the resistance increases in the manner shown by the curve until at 45 percent of rotation the resistance has a value of about 180 ohms. The calculated value at this point is 181.9 ohms. This is the resistance of section 17 of the winding. The value for 70 percent of rotation, which marks the end of section 18 of the winding, is 401.3 ohms. The total resistance is 900 ohms, attained upon 100 percent rotation, when the 20 wiper of the potentiometer will be in engagement with a turn of the winding which is soldered to terminal 12.

The spacing of the turns on the strip may now be explained. As indicated in Fig. 1, section 19 30 is wound on the strip with a decreasing spacing, section 18 with an increasing spacing, while in section 17 the spacing again decreases, from left to right.

The winding of section 17 is started with a 35 wide spacing which if continued would cause the resistance curve to take a straight line form such as indicated by the line 25. By means of a progressively decreasing spacing, however, a progressively increasing number of turns per 40 unit distance along the strip is obtained, whereby the resistance curve is made to conform to section R1 of the required curve.

The length of section 17 in percent of rotation 45 (45 percent) is so selected that the resistance curve R1 can be obtained, without exceeding the permissible value for Q at either end of the section; in fact the values of Q are well within the range that can be employed. The average value of Q as calculated for the first sub-section of 50 section 17 extending from 0 rotation to 5 percent rotation is 2.57 and for the 9th sub-section extending from 40 percent rotation to 45 percent rotation is .43.

The tapered section 18 of the wire has a greater 55 slope than is required to obtain the resistance curve R2 with a uniform spacing of the turns. In other words, if the section were to be wound with the same spacing as used in the 9th sub-section of section 17 the resistance would increase 60 too fast and the resistance curve would take the general direction of line 26. Section 17 is therefore wound with an increasing spacing, or value of Q, which for the 14th sub-section extending from 65 percent rotation to 70 percent rotation has an average value of 2.14.

In section 19, as in section 17, the wire is of uniform diameter and the resistance curve for a winding with uniform spacing would have the general direction of line 27. A decreasing spacing is therefore necessary in order to obtain the 70 resistance curve R3. There is a lag, however, due to the excessive taper in section 18, so that in the 15th sub-section extending from 70 percent rotation to 75 percent rotation the average 75 value of Q is 2.27. The value decreases to 1.91

in the 16th sub-section and continues to decrease in the remaining sub-sections until in the 20th sub-section it reaches .84.

It will be seen that the invention may be employed in the manufacture of resistance elements having a wide variety of resistance curves, including curves that cannot be obtained merely by a varying spacing of a uniform diameter wire on a strip of uniform width. Such curves could be obtained with a tapered wire, but only at a considerably greater cost, for the wire shown in Fig. 3, having only a short tapered section equal in length to the length of the electrolytic cell system in which it is made is much less expensive than a wire which is tapered throughout its length. In general, a resistance wire made in accordance with the invention should be designed with a section such as 17 which is as long as can be used, in order to obtain the maximum economy. This principle was not adhered to fully in the design of the resistance element shown herein, as will be evident from the fact that the maximum value of Q in section 17 is less than 3 while the minimum value is considerably greater than .25.

In some cases it will be possible to omit the last section such as 19, using a resistance wire having only two sections one of which is of uniform diameter and the other of which is tapered to a smaller diameter. Or the required resistance curve may be such as to require or make it more convenient to use a wire comprising a tapered section and a section of uniform diameter which is the same as the smaller diameter of the tapered section.

It will be understood that the values given herein apply only to the specific resistance element shown. The invention could have been explained in general terms but it is believed that the description of a specific embodiment of the invention with the actual values of resistance, turn length, spacing, etc. will promote a clearer understanding of the invention and give a better idea of its practical application.

The values for other specific resistance elements and the data required for setting up the winding machine can readily be calculated by following the procedure explained in the application Serial No. 602,813, previously referred to.

The invention having been described, that which is believed to be new and for which the protection of Letters Patent is desired will be pointed out in the appended claims.

I claim:

1. A resistance element having a non-linear resistance curve comprising a continuous resistance wire wound on a strip of insulating material of uniform cross-section, said wire comprising a section of uniform diameter and a tapered section, and the said resistance curve being obtained in part by the taper in said tapered section and in part by a varying turn spacing in both sections.

2. A resistance element having a non-linear resistance curve, comprising a continuous resistance wire wound on a strip of insulating material of uniform cross-section, said wire comprising two sections of different diameter joined by a tapered section, and the said resistance curve being obtained in part by the taper in said tapered section and in part by a varying turn spacing in all three sections.

3. A resistance element comprising a winding of resistance wire on a suitable support, said wire having two sections of different diameter joined by a tapered section, said two sections being

wound with a varying spacing which increases in the same direction and said tapered section being wound with a varying spacing which increases in the opposite direction.

4. A resistance element having a logarithmic resistance curve, comprising a winding of resistance wire wound on a suitable support, said wire comprising a section of uniform diameter which is wound on said support with a decreasing turn spacing, a tapered section which is wound on said support with an increasing turn spacing, and a section of uniform diameter less than the diameter of the first section which is wound on said support with a decreasing turn spacing.

5. A non-linear resistance element, comprising a winding of resistance wire on a strip of insulating material of uniform cross-section, said wire having a section in which the wire is of uniform diameter and is wound on said strip with a decreasing turn spacing and an adjoining section in which the wire is tapered and is wound on said strip with an increasing turn spacing.

6. A non-linear resistance element, comprising a continuous winding of resistance wire on an insulating strip of uniform cross-section, said winding having two adjacent sections in one of which the resistance wire is of uniform diameter and in the other of which the resistance wire is tapered to a smaller diameter, the said section in which the wire is of uniform diameter having a varying turn spacing which decreases in the direction of the section in which the wire is tapered.

7. A non-linear resistance element, comprising a continuous winding of resistance wire on an insulating strip of uniform cross-section, said winding having two adjacent sections in one of which the resistance wire is of uniform diameter and in the other of which the resistance wire is tapered to a different diameter, the said section in which the wire is of uniform diameter having a varying turn spacing which increases or decreases in the direction of the section in which the wire is tapered depending on whether the wire in the latter section is tapered to a larger or smaller diameter.

8. A resistance element having a non-linear resistance curve, said element comprising a continuous winding of resistance wire on an insulating strip of uniform cross-section, said winding having a section in which the resistance wire is of uniform diameter and is wound on the strip with a turn spacing which gives the corresponding section of said resistance curve the required direction, said winding also having an adjacent section in which the resistance wire is tapered more than is necessary to give the corresponding section of said resistance curve the required direction and is wound on the strip with a turn spacing which compensates for the excessive taper.

9. A resistance element having a non-linear resistance curve, said element comprising a continuous winding of resistance wire on an insulating strip of uniform cross-section, said winding having a section in which the wire is of uniform diameter and is wound on the strip with a turn spacing which gives the corresponding section of said resistance curve the required direction, said winding also having an adjacent section in which the resistance wire is tapered and is wound on the strip with a varying turn spacing such that the combined effects of the taper and turn spacing give the corresponding section of the said resistance curve the required direction.

10. A resistance element having a non-linear resistance curve, said element comprising a winding of resistance wire having equal length turns, said winding having first and third sections in which the wire is of uniform diameter, the wire in the third section being smaller in diameter than it is in the first section, and a second section in which the wire is tapered, the said first and third sections having a decreasing turn spacing to give the corresponding sections of said resistance curve the required direction, and the taper on the wire in the second section being enough greater than is required to give the corresponding section of the resistance curve the required direction so that the turn spacing in the second section can be increased without abrupt change from the narrow spacing at the end of the first section to the wider spacing at the beginning of the third section.
